UNITED STATES PATENT OFFICE.

FRANZ RAUCHWETTER, OF BERLIN-FRIEDENAU, GERMANY.

KEYBOARD ADDING-MACHINE.

1,239,622.

Specification of Letters Patent. Patented Sept. 11, 1917.

Application filed December 29, 1916. Serial No. 139,682.

To all whom it may concern:

Be it known that I, FRANZ RAUCHWETTER, a subject of the German Emperor, and residing at 38 Stubenrauchstrasse, Berlin-Friedenau, Germany, have invented certain new and useful Improvements in Keyboard Adding-Machines, of which the following is a statement.

The present invention relates to improvements in key-board adding-machines, and in particular to the operating gear therefor. The adding-machines to which the present invention refers in particular are such which have abutments adjustable in advance according to their face value, which abutments limit the travel of the transmitting means to the counting gear, when said transmitting means are operated by the main shaft of the machine.

The essential feature of the present invention consists in the coöperation of bell-cranks set in advance by the numeral keys with rocking clips of known design, operable by the main shaft of the machine, the jaws of which clips are provided with notches corresponding to the numerals 1-9, with which they grip pins or abutments provided on the said bell cranks in such a manner that the stroke of said jaws is thereby limited.

In the accompanying drawing the present invention has been exemplified in a constructional form; Figure 1 is a side elevation, partly in section; Fig. 1^a is a side view of the keyboard, partly in section, illustrating the engagement between the bell cranks and a ratchet bar. Fig. 2 is a front elevation partly in section; Fig. 3 is a side elevation of a row of keys with one key depressed, likewise partly in section, and Fig. 4 is a perspective view of the oscillating arrester bar; Figs. 5 and 7 are front and side elevation, respectively of a part of the machine shown in Fig. 1, showing in particular the bell-crank gear in the same position as in Fig. 1, and Fig. 6 shows the same gear in a different position, namely in engagement with the counting gear wheel 22. Figs. 8, 9, 10 and 11 are various parts shown in Figs. 5, 6 and 7, illustrated individually.

As may be seen from the drawing, the keys 1 operate bell cranks 2 which are under action of springs, which bell-cranks displace a bar, 4, having noses 3 in the following manner according to the face value of the key depressed:

The bell-cranks 2 have two downwardly projecting arms 5 and 6 (Figs. 2 and 3). The arms 5 are all of the same length, while the arms 6 gradually decrease in length. When a key is depressed (Fig. 3) the arm 5 of the bell-crank operated engages in a notch 7 in a bar 8 extending beneath arm 5, after said bar has been previously drawn down by the passage of arm 5 and thereby released a previously set bell-crank 2 and the keys coupled thereto. At the same time the arm 6 of the operated bell-crank 2 will shift the bar 4 having noses 3 by a given distance. This bar 4 is coupled by means of a bar 9 with a bell-crank 11 rocking on pivot 10, the arm of which bell-crank is thereby turned through an angle in proportion to the face value of the key depressed. To the free end of bell crank 11 is fitted a pin 12, which will therefore assume a given position corresponding to the key depressed. This pin 12, in doing so, rocks in the path of jaws 13' and 13'' of a clip 13. These jaws 13' and 13'' are provided in known manner with notches 14, the number and position of which correspond to the numerals 1-9 of one row of keys. After the bell-crank 11 and its pin 12 have been set the said clip 13 is operated by aid of a connecting rod 16 from the main shaft 15 of the machine to which it is connected in any suitable manner well known with machines of this kind.

The said connecting rod 16 operates on a lever 17 rocking on a fixed pivot 23, being coupled thereto with a pin 16'; this lever 17 again operates a lever 18 by means of a pin 17' engaging in a slot in the latter. The lever 18 is thus coupled both with the jaw 13' and the jaw 13'' of clip 13, namely with jaw 13' by a pin 13^a, which is fitted in a hole in jaw 13' and engages in a small slot in lever 18; with jaw 13'' by means of a pin 18' which engages in a hole in said jaw. The jaws 13' and 13'' rock on pin 19. When, therefore, the bar 16 is operated (see Fig. 6) the jaw 13' will by means of lever 17 and lever 18 be turned on pin 19 until a corresponding notch 14 of said jaw engages with the previously set abutment pin 12 of bell-crank 11. Thereby the further travel of the jaw 13' is prevented.

When, now, the bar 16 is moved further the lever 18 will rock with its slot on pin 13^a of jaw 13', which is now stationary and will thereby rock the jaw 13'', to the lower end of which it is linked at 18', on pin 19

until the corresponding notch 14 of jaw 13" likewise engages with the abutment pin 12 of bell-crank 11 (see Fig. 6). By the oscillation of jaw 13" the extended arm 20 of the same is likewise rocked and will thereby rock the toothed sector 21, which transmits the rotation to the counting gear wheel 22.

The counting gear is provided in known manner with tens transfer for additions. 10 The machine may be operated by means of an operating lever, a crank handle or also by a suitable motor.

I claim:

15 In keyboard adding machines in combination with the main shaft, abutments settable by keys in accordance with the face value of the latter, said abutments limiting the travel of the transmitting means operated by the main shaft, bell cranks, rocking 20 on fixed pins in proportion to the face value of the keys depressed, clips operable from the mainshaft, the jaws of said clips having notches corresponding to the numerals 1-9, the said bell-cranks having arms carrying

abutment pins, said abutment pins adapted 25 to be engaged by said jaws, numbered keys, bell-cranks under action of springs and engaged by said keys, said bell-cranks having each two downward extending arms, the ones of said pairs of arms of equal length, 30 the others of said pairs of arms gradually decreasing in length, a bar having abutments, said abutments adapted to be engaged by said gradually decreasing arms and to thereby shift the said bar by a given 35 length corresponding to the face value of the respective key depressed, an arrester bar, for arresting the keys in their depressed position, elastically and hinged suspended, and adapted to be released and arrested by 40 said arms of equal length.

In testimony whereof I have hereunto set my hand in the presence of two subscribing witnesses.

FRANZ RAUCHWETTER.

Witnesses:

HENRY HASPER,
ALLEN F. JENNINGS.
